UNITED STATES PATENT OFFICE.

RICHARD TEEGARDIN, OF LIMA, OHIO.

DESIGN FOR A FODDER-FORK BLADE.

SPECIFICATION forming part of Design No. 32,853, dated June 19, 1900.

Application filed May 21, 1900. Serial No. 17,486. Term of patent 7 years.

To all whom it may concern:

Be it known that I, RICHARD TEEGARDIN, a citizen of the United States, residing at Lima, in the county of Allen and State of Ohio, have **5** invented a new and original Design for Fodder-Fork Blades, of which the following is a specification.

My invention relates to a design for fodder-fork blades, which is illustrated in the accompanying drawing.

My design consists of the two horn-shaped fork members *a*, connected at their inner ends, and the relatively-elongated centrally-projecting and pointed fork member *b*, which

has its inner end united to and at the junction of the horn-shaped members *a*.

Having thus described my invention, what I claim, and desire to secure by Letters Patent, is—

The design for a fodder-fork blade substantially as herein shown and described.

In testimony whereof I have hereunto set my hand in the presence of two subscribing witnesses.

RICHARD TEEGARDIN.
